Fig. 6

Fig. 1 is a top plan view of a tile showing my new design, the uniform stippling representing surfaces in a common plane and the graded stippling representing planar areas inwardly inclined from said plane.

Fig. 2 is a cross-section on the line 2—2 of Fig. 1.

Fig. 3 is a cross-section on the line 3—3 of Fig. 1.

Fig. 4 is a cross-section on the line 4—4 of Fig. 1.

Fig. 5 is a top plan view of a modified form of the tile shown in Fig. 1 wherein the centro-symmetrically arranged contrasting areas are on the same plane.

Fig. 6 is a cross-section on the line 6—6 of Fig. 5.

The essential features of my design for a tile reside within the portions shown in full lines, which portions are characterized by the contrasting areas arranged in centro-symmetrical relation on the face thereof, substantially as shown.

I claim:

The ornamental design for a tile or similar article, substantially as shown and described.
